DESIGN FOR A PLEATED NECKTIE

Jacob B. Grinoch, New York, N. Y.

Application March 5, 1947, Serial No. 137,363

Term of patent 14 years

(Cl. D3—16)

To all whom it may concern:

Be it known that I, Jacob B. Grinoch, a citizen of the United States, residing at the Bronx, in the county of Bronx and State of New York, have invented a new, original, and ornamental Design for a Pleated Necktie, of which the following is a specification, reference being had to the accompanying drawing, forming part thereof, in which

Fig. 1 is a perspective view of a pleated necktie embodying my new design, showing the pleated front and the inside of the unpleated back.

Fig. 2 is a sectional view taken on the line 2—2 of Fig. 1 illustrating in detail the pleated portion which is the dominant feature of my design.

I claim:

The ornamental design for a pleated necktie, as shown and described.

JACOB B. GRINOCH.
